UNITED STATES PATENT OFFICE

ERNST BAUMBERGER AND EMIL HEUSSER, OF AARAU, SWITZERLAND, ASSIGNORS TO
FABRIK ELECTRISCHER APPARATE SPRECHER & SCHUH, AKTIEN-GESELLSCHAFT,
OF AARAU, SWITZERLAND, A JOINT STOCK COMPANY OF SWITZERLAND

TIME LIMIT RELAY

Application filed November 7, 1927. Serial No. 231,663.

This invention is a novel time-limit relay, or electrical controlling or protective device for automatically cutting out, isolating or changing portions of electric systems or circuits, especially for interrupting the circuit in portions affected by dangerous current overloads, without interrupting the current supply in normal portions. The invention is herein shown applied more particularly to 10 an overload relay of the inverse time-limit type, wherein the operating period or interval preceding the tripping or disconnecting of the circuit is of shorter duration in cases where the overload is greater, and vice versa. 15 The invention is of utility in various fields where such relays have been used, notably in the transmitting systems or network of electric circuits wherein electric current for light and power are distributed over the various sections or subdivisions of a city, or other geographical area; also in interior distributing systems, and for the protection of distance transmission systems, cables, etc.

Among the objects of the present invention 20 are to afford an overload relay of the kind referred to which will be accurate and reliable in action, efficient in use, and convenient of control; to provide the ability to be readily and accurately adjusted to variations 25 of conditions encountered; and to present a design or structure which is simple, compact, rugged and durable.

Another object is to allow for the adjustment, to suit local conditions of load, of the 30 point at which the undue increase or change of load causes the response or starting of the movement or travel which terminates in the tripping or interrupting of the main current, and to do this in a manner not to affect the 35 tripping characteristic or action, nor to disturb the correct operation of the protecting operation; in other words to render the tripping characteristic independent of the starting of the tripping action. By maintaining 40 the characteristic of fixed and dependable

character the proper operation or tripping of several relays in the same network is assured.

Another object is to render the current response element of the apparatus separate from and having an action independent of 50 the time element or driving means, although controlling the operation of the latter.

A special object is to provide for an adjustment of the current response point in a continuous manner, that is, to any desired value 55 within the range of the instrument, and without altering the tripping action as predetermined by the characteristic.

Another object is to provide for extending the adjustment range in a simple manner so 60 as to render a given relay of greater scope of utility. Another object is to provide for a fine and accurate adjustment of the time interval or tripping period for each adjustment of the current response element, permitting 65 the cooperative and selective operation of a large number of current interrupters or switches in the same system.

A further object is to provide for the instantaneous restoration of the relay to its 70 starting condition whenever, during its period of operation, the current may be reduced safely, for example may drop to a point ten per cent below the predetermined response value, thus ensuring the full time 75 of operation and avoiding the cutting out of sections having no prolonged dangerous overload, for example when the system is subjected to a series of heavy current surges in advance of the final overload and disconnection.

A further object and advantage of the present invention is its operation with very low power consumption, rendering it therefore available with the bar type of current 85 transformer, as herein indicated.

Other and further objects and advantages of the invention will be explained in the hereinafter following description of an illustrative embodiment thereof or will be under 90

stood to those conversant with the subject matter of overload relays. To the attainment of such objects and advantages the present invention consists in the novel time-limit 5 overload relay and the novel features of operation, combination, arrangement and construction herein illustrated or described.

In the accompanying drawings Fig. 1 is a diagrammatic view of an apparatus embodying the present invention, with certain parts shown physically in what may be considered left elevation, corresponding with Fig. 8.

Fig. 2 is the characteristic curve of the apparatus of Fig. 1.

Fig. 3 is a left elevation of the preferred form of the magnetic switch and signal device, shown only diagrammatically in Fig. 1, and not included in Figs. 8 and 9.

Fig. 4 is a vertical section taken through the motor magnet and showing the motor disk, looking from the rear, and may be considered as taken on the plane 4—4 of Fig. 1.

Fig. 5 is a section on the plane 5—5 of Fig. 4, looking from below, the motor disk broken 25 away.

Fig. 6 is a left elevation of the braking magnet of the motor, partly broken out to show details of its mode of adjustment.

Fig. 7 is a bottom view of the elements 30 shown in Fig. 6.

Fig. 8 is a left elevation of an actual embodiment of the timing portions of the apparatus in their preferred form, and the current responsive element controlling the operation thereof.

Fig. 9 is a bottom view of the mechanism shown in Fig. 8.

The apparatus as a whole may be considered as comprising certain cooperating elements or mechanisms which may be designated respectively as, first, the tripping or switch mechanism by which an interrupter is operated to break the line circuit, second, the motor element or driving mechanism operating 40 at variable speed for actuating the time element, third, the coupling element or current operated mechanism for starting the time element in operation by coupling it to the motor mechanism, and finally, the time element or switch closing mechanism which 45 is arranged to be actuated by the motor element but under the control of the coupling element; which elements will be described in the order stated.

A conventional form of interrupter 13 is shown in Fig. 1, with line conductors 11 and 12 at the left or line side, and load conductors 14 and 15 at the right or load side, extending to a system of lamps, motors or other translating devices, or to transmission systems, which are to be protected from overload.

The interrupter 13 may be in the nature of a double pole switch operated by a latch or toggle 16, these parts being shown in the diagram as in their closed or set position, the

toggle having a resetting handle 17 which may be thrown back from the dotted line or open position to the full line or closed position to restore the circuit. The toggle 16 may be tripped by shifting the toggle levers 70 to a reverse position, upon which a spring or gravity will retract and open the interrupter. This tripping operation may be effected by a solenoid 18 comprising a core 19 adapted to deliver a tripping blow upon the toggle, with 75 a coil 20 arranged to be energized when the circuit is to be interrupted.

The coil 20 is in a circuit which is shown to comprise also a wire 21 between the coil and a battery 22, a wire 23 from the battery 80 to a main or control switch 24, and return wires 25 and 26 from the switch to the coil. The switch 24 is shown as comprising a pair of contacts 27 adapted to be interconnected by a flared contact 28, suitable for carrying the heavy tripping current. The contact 28 is carried on a core 29 movable in a solenoid coil 30 arranged to shift the core and thus close the contact, when energized, opposed by a spring or gravity. An extension of the 85 solenoid core is arranged to throw a trigger 31 which releases and drops a signal or semaphore 32, which thus indicates the defective condition, and which may readily be restored by hand.

The solenoid 30 may be energized by the same battery 22, by the following connections. A wire 34 is shown extending from the coil to the wire 26, and a wire 35 from the wire 23 to a button 37, and a wire 36 from the coil to the opposite button 38. The word wire is intended to include any conductor or connection. The two buttons 37 and 38 are normally disconnected but are adapted to be connected by a light contact 90 piece 39 suspended in open position by a balance spring 40, these elements 37 to 40 constituting what may be termed a pilot switch or circuit closer 41 for the main switch 24. When the contact piece 39 is lifted sufficiently to connect the contacts 37, 38 this 100 delivers the battery current into the solenoid coil 30 which thereupon shifts the core 29 to close the main switch 24. This acts to drop the signal 32, and makes a direct circuit to admit the full current of the battery into the coil of the tripping solenoid 20, thus causing its core to move, opposed by a spring or gravity, in a manner to trip or throw the toggle 16, which thus permits the interrupter 110 115 120 125 130 135 140 145 150 155 160 165 170 175 180 185 190 195 198 200 205 210 215 220 225 230 235 240 mains broken until the interrupter is reset by its handle 17; although the main switch can be arranged to be held closed by its current until released by the operation of the interrupter.

The driving mechanism will next be described and later the coupling mechanism and time mechanism, the latter operated by the driving mechanism and operating the switch mechanism.

The current for operating the relay may be a reduced current taken by induction from one of the line wires, a transformer 45 being conventionally indicated for this purpose, applied to the line wire 11, although separate transformers for the two electromagnets could be used. The transformed current is utilized both in the magnet of the drive mechanism and in the magnet of the coupling mechanism, giving actions which vary with the current, whether normal or abnormal, in the line wires.

The connections between the transformer and the motor magnet, and the construction of the latter may be substantially as follows. One terminal of the transformer coil 45 is shown connected by wires 46 and 47, and the other terminal by wires 48 and 49, with the coil 50 of the motor magnet 51. This magnet may comprise a laminated iron core 52 substantially of the shape of the letter C, with an upstanding leg 53 shown within the coil 50, although the coil can be placed elsewhere. For purposes that will be described the lower pole 54 of the magnet 51 is shown of substantially reduced cross section, see Figs. 1, 4 and 5; and the opposite or upper pole 55 is similarly reduced in cross section. Each of these reduced poles may have a copper mass, or so-called shading coil 56 adjacent the pole and cooperating in the electric actions as will be further described.

The armature of the motor may consist, as in the driven element of a watt meter, of a disk 60 mounted on a shaft 61 and so arranged that the outer part of the disk may be rotated in the air gap between the poles 54 and 55 of the motor magnet. The mode of action (Ferraris principle) by which such disk is driven is well understood, being the result of the eddy currents induced in the disk by the alternating magnetism, and the cooperation thereof with the varying lines of magnetic flux. When the current in the motor magnet circuit rises to or above a certain amount the armature disk 60 will commence to rotate, and will turn with a speed which normally corresponds with the current, and therefore with the rate of consumption of current by the load comprised in the system or installation controlled by the relay.

In such a motor it is common to employ a restraining or braking magnet, and such a magnet 63 is shown, this being preferably

a permanent magnet, with its poles at opposite sides of the disk 60 at a point removed from the motor magnet. It is important that the braking or damping magnet shall be in such relation to the disk that the speed of the latter will correspond to the value of current flowing at any given moment, and there is herein shown an effective adjusting device permitting the magnet to be accurately set in its relation to the disk; see Figs. 6 and 7. On a fixed frame part or bracket 64 are mounted, first a main screw 65 passing loosely through the bracket and threaded into the magnet, and surrounding it three other screws 66 threaded into the bracket and contacting with the underside of the magnet. By cooperatively loosening the several screws, and swinging the magnet to its desired peripheral position, and exactly centering it, an adjustment can be made to give the relay the characteristics or qualities required for the particular use to which it is to be put.

The driving mechanism or time motor thus described operates through the shaft 61 to work the time mechanism when coupled thereto. The motor is inoperative at low currents, but starts into action well below any substantial overload, in fact below the normal rated current of the relay, and it operates with a speed which increases with the current that operates it, thus giving higher speeds with higher overloads, and vice versa.

The remainder of the apparatus comprises the time mechanism for closing the pilot switch 41, together with mechanical connections from the motor disk 60, or shaft 61, for operating the time mechanism, such connections being normally uncoupled, and an electromagnet or equivalent means for effecting the coupling or clutching of the connections, under certain predetermined overload conditions, to start the operation of the switch closing or time mechanism, and for uncoupling the connections to restore the mechanism when the overload conditions terminate.

It will be convenient first to refer to the coupling or clutching magnet 70, which consists of an iron core, preferably of U-shape, carrying one or more coils 71, which may be in series, connected by a wire 72. These are preferably voltage or potential coils, shown connected at one side by a wire 73 with the wire 46, and at the other side by wires 74 and 75 with the wire 48, being thus in parallel with the motor magnet coil 50. A resistance 76 is shown interposed in series between the wires 74 and 75, controlled by a manual contact screw 77 by which the resistance can be thrown into circuit or cut out at will, to change the range of current responsive operation of the magnet 70, as will be further explained.

The coupling magnet 70 is arranged to effect magnetic pull upon an armature 79

mounted on a movable or swinging support 80 shown as swivelled or pivoted upon or by means of a shaft 81. As will be explained the magnet pull normally is incapable of drawing the armature, but when the current in the magnet coils exceeds a predetermined value the armature is drawn to the magnet to swing the support 80 and effect the coupling or clutching operations to be described.

10 The operating element of the time mechanism comprises any suitable traveling member such as an arm 82, which is shown for convenience mounted swingingly by pivot 83 on the armature support 80. The traveler or advancing arm 82 is formed with a finger 84 adapted to press upon and close the electric contact or pilot switch constituting part of the tripping means for the interrupter. Considering Fig. 1 as an elevation view, the traveling arm 82 is swung upwardly and eventually effects the closing of the switch and the operation of the interrupter, unless the arm should be uncoupled or released and allowed to return to its normal position within the time period required to travel to the switch.

15 The driving and coupling connections by which the motor shaft 61 causes the travel of the arm 82 may be as follows. Mounted directly on the arm 82 by means of a flexible bar or spring strip 85, is shown a toothed rack or segment 86, arranged to engage with and disengage from a worm 87 mounted on the motor shaft 61. Normally the rack and worm are disengaged by reason of the rack standing beyond the work, being yieldingly so held by the spring 94; but when the magnet 70 draws the armature 79 this swings the support 80 and arm 82 and carries the rack 86 into engagement with the worm, so that from this instant the coupling is in effect, and the rotation of the motor shaft effects the progressive travel or forward motion of the arm toward the tripping switch or contact bar 39. The purpose of the flexible mounting of the rack 86 on the bar 82 is that, after the arm has reached the limit of its movement and has closed the contact, the continued action of the worm 87 on the rack 86 will be prevented from causing injury or breakage, the easily displaceable rack being swung laterally aside at each rotation of the shaft and snapping back into engagement, thus holding the arm at the limit of its travel.

20 The time or period of travel of the traveler or time arm 82 depends on two factors, first, upon the speed of the traveler, and therefore, upon the variable speed of the shaft 61, which is reduced considerably by the worm and wheel connection to the traveler, and second, upon the distance to be traveled from the initial position of the traveler, as shown in the diagram, to its final position in which it effects the actual closing of the pilot switch. This travel distance or space may herein be varied or adjusted and set at will to a desired

25 distance by any convenient device, such as the adjustable stop 88. This stop is indicated diagrammatically in Fig. 1 as standing in its lowest set position, being carried on an adjustable support 89. The traveling arm 82 rests normally against the stop, but the stop is adapted to be set at varying positions, which may conveniently be predetermined by its pointer or index 90 moving along a scale 91. The scale is shown subdivided into small units representative of the amount of travel required to close the contact. The stop is indicated as adjusted into its lowest or normal position marked 1.0. Ten spaces higher the scale is marked 0.5, and nine spaces beyond that 0.05, for adjustment to reduce the space and time interval. The full or unit distance from 0. to 1.0 is shown divided into 20 spaces representing fractions of the full time period.

30 To oppose the pull of the magnet upon its armature 79, and to retract the armature when released, the armature is shown as provided with an extension 93 to which is attached a spring 94. The resisting tension of the spring 94 is one of the factors which determines the movement of the armature and thereby controls the coupling of the drive elements 86, 87, another factor being the varying strength of the magnet 70. In order to enable adjustment of the pull of the spring, and thereby to determine the strength of current in the coils of the magnet which will cause the armature to be drawn and effect the coupling action, the spring is shown as adjustable. Thus the end of the spring 94 which is not connected to the extension 93 is shown connected to an adjustable support or arm 95, which arm is swingable about a pivot 96. For adjustably swinging the arm it is shown as formed with a contact surface 97 engaged by a pin 98 mounted on an adjustably swingable lever 99, which lever is fulcrumed at 100 and may be shifted and set at will with its index end 101 at any position along a scale 102 or supplemental scale 102^a. The contact surface 97 may be in the nature of a cam, and is preferably of such character or curvature that equal movements of the lever along the scale effect equal increments in the tension or pulling resistance of the spring 94, thus providing for intelligent adjustment of the action of the coupling magnet 70.

35 The coupling and time elements thus described on the diagram of Fig. 1 are substantially the same in principle on the elevation view of Fig. 8 and the bottom view of Fig. 9 of a practical embodiment. The coupling magnet 70 and its coils 71 are the same while the remaining parts correspond. A frame element 78 is shown which may be one of the walls of the instrument, and other enclosing walls will be understood. The magnet armature 79 is provided with spacing screws 79^b preventing actual contact with the poles of the magnet. The swinging support 80 may

be struck from sheet metal, and has its pivot or fulcrum shaft 81 mounted in a fixed bracket 78^b extending downwardly from the frame 78. The traveler or time arm 82 has a screw 5 adjusted fulcrum 83 on the support 80, and the arm carries an offset finger 87 for closing the contact 41. Also mounted on the support 80 and alongside of the arm is the flexible strip 85 carrying the curved rack 86 engageable with the worm 87 of the motor shaft. The adjustable stop 88 for the return movement of the traveler or time arm is shown mounted on a swinging lever 89 fulcrumed at one end 89^b and having its free end arm 10 ranged as a pointer 90 running along the scale 91 by which is predetermined the distance of travel of the arm.

The armature 79, in its movement from the magnet, is limited by an adjustable stop 20 92, cooperating with the bracket 78^b. The retracting spring 94 is shown operating directly on the armature, while the other end of this spring is formed with a loop or hook 94^b initially engaged in any one of a series of 25 notches 95^b in the cam arm 95, by which the tension of the spring may be additionally adjusted. The arm 95 is shown pivoted to the frame at 96, and it is formed with a curved surface 97 adapted to be adjustably 30 engaged by a pin 98 mounted on the adjusting lever 99. The pin 98 is preferably itself adjustable along the lever for accurately setting the initial adjustment, namely by a nut and slot device 98^b. Like the lever 89 the lever 35 99 is pivoted to the frame, by stud 100, while its free end is formed as a pointer 101 shiftable along a primary scale 102 and a supplemental scale 102^b.

In describing the operation of the illustrated relay a particular set of data may be 40 assumed. Thus the relay may be what is rated as a one ampere relay. The normal current in the relay, without overload, is 1 ampere or less. The transformer 45 may be of 45 such character that a full normal current of 800 amperes for example in the line wires will induce an operating current of 1 ampere in the relay. The disk motor may be such as to be continuously in operation at all relay currents above say 0.3 or 0.4 amperes, in other 50 words the motor commences rotation when the current attains between 30% and 40% of the rated current, and thereabove the motor speed increases with increase of relay current, 55 up to a predetermined limit as will be described.

The spring 94 of the electromagnetic coupling element is accurately standardized to have such qualities that when its adjusting 60 lever is set at 1.2 it will effect a pull on the armature which requires a starting current of 1.2 amperes to overcome, and when the pointer is adjusted to 2.0, as shown in the drawings, a current of 2 amperes is necessary. Continuous adjustment to any point 65

between these limits is therefore possible by properly setting the pointer along the calibrated scale 102. This is on the understanding that the resistance 76 is shunted out by the closing of the contact 77, as shown; and when the contact is opened a greater current is required to draw the armature and couple the time member, and the pointer will then be observed in conjunction with the second scale 102^b, giving an elevated range of adjustment, from 2.2 up to 3.8 amperes. In this way the one ampere relay is made to serve an extended use. The calibration of the two scales is such that each division represents an equal increment of tension, due to the shape of the cam 97.

The characteristic curve as drawn in Fig. 2 shows the dependency between the overcurrent strength and the time of relay operation when set for the full or unit period, and with this invention this relation will be consistent for all adjustments of the relay and for all of a number of similar relays in the same system. The characteristic is independent of the setting for the starting current, and not affected by any adjustment thereof, wherefore the correct operation of the protecting devices will not be disturbed by any change of current adjustment. In other words the time element and the current element of the relay 90 operate independently of each other; the speed of the motor and therefore the period of the relay depend upon the strength of overcurrent, but are not influenced by the current adjustment of the spring 94 which controls the starting of the operation or travel of the time member 82.

The characteristic curve shown in Fig. 2 indicates that at a current of 1.2 amperes the time element or traveler 82 will travel its full or unit distance in 20 seconds. At a current of 2 amperes the full travel period will be 10 seconds; at 5 amperes it will be about 5.7 seconds; at 10 amperes the interval will be 5 seconds, and for any current above 10 amperes the time interval will remain 5 seconds, which constitutes a minimum period of operation of the relay for excessive overloads. The attainment of this advantageous feature of the invention will be explained further below. It 105 will be understood of course that where the overload current is variable it will be the average current which will determine the time interval of operation.

It will be further understood that the time interval or travel period for any given overcurrent as indicated by the characteristic curve is merely the interval or period required for the time member or traveler 82 to travel the full or unit distance, namely from 1.0 to 0.0 on the scale 91, at which latter point the pilot switch is contacted and the main switch closed to trip the interrupter. Stated another way the speed of the travel is such, at any given current, as to traverse the unit dis- 110 115 120 125 130

- tance in the indicated time or period. The actual time of operation of the relay may be reduced at will below the indicated figure to any desired degree by adjustment of the stop 5 88—90 along the scale 91, to reduce the full or unit distance to a fractional distance. Thus if the stop be adjusted to 0.5 the operative period will be half of the full or indicated period; if it be adjusted to 0.05 the 10 operative period will be 1/20 of the full period, so that with this adjustment a high overload may result in the interruption of the line current in as low as 1/20 of 5 seconds or 1/4 second. The adjustment along the time or period scale 91 is continuous, giving all adjustments up to the full or unit period.

- As already stated, the time member or traveler 82 travels to and operates the switch in a period which varies inversely as the current up to a predetermined value of current, 20 namely 10 amperes in the illustrated embodiment, and above that in a constant minimum period, namely 5 seconds or such fraction thereof as may be indicated by the setting of 25 the stop 88. The features affording this operation will now be explained.

The rotary speed of the time motor depends upon the motive force or torque which results from the magnetic field in the motor magnet, and this, with a given number of 30 turns of winding, is proportionate to the number of amperes of current traversing the coils; but this general rule is qualified by the phenomenon that the field of the motor magnet may reach a saturation point, and that when this point is reached an increase of current strength will not increase the magneto motive force nor the driving torque or speed of the motor. This invention takes advantage of this principle by so designing, arranging and combining the parts that the motor magnet will reach the saturation point when the disk is being driven at the correct speed to produce the minimum full time interval desired, for example in this case 5 40 seconds. Stated more specifically, when the induced current in the relay reaches about 10 amperes in the illustrated relay, the motor disk will be driven at its maximum speed, which is such as to trip the interrupter in the period of 5 seconds; and the magnet having 45 reached the saturation point any further increase of current will afford no greater motive force, the torque remaining constant 50 from 10 amperes up, so that the speed of travel of the time member remains constant, and the time period or interval consequently remains constant at 5 seconds.

These results are herein obtained by a proper predetermination of the magnetic saturation point of the motor magnet, namely by a correct reduction at the poles 54 and 55 of the cross sectional area of the core of the magnet. When the current increases to a 60 value at which the poles become saturated

with magnetic flux the permeability of the iron is reduced to that of air, so that additional flux generated by a further increase of current will be mere leakage flux and will not traverse the disk. Both of these poles are 70 seen in Figs. 1, 4 and 5 to be substantially smaller than the cross section of the body of the core 52. In the case, for example, of the one ampere relay illustrated, in which the saturation point is reached at ten times the 75 rated current, or at 10 amperes, the full cross sectional area of the magnet core may be in the neighborhood of .50 square inches, while the reduced cross section of the opposite poles may be in the neighborhood of .09 80 square inch. Alongside of the reduced cross section of iron core, at each pole, is shown the copper block or ring 56 operating as a shading coil or short circuit winding and taking part in the electromagnetic actions, secondary currents being induced in the copper rings or coils 56, producing a lagging field which by interaction with the field of the main coil produces the driving action of the disk. 90

With the described arrangement, as the relay current is increased from 1 ampere to 10 amperes the speed of the motor will be increased in such manner as to afford a decreasing time or period of operation, in accordance 95 with the characteristic curve, until, at 10 amperes, when the iron of the magnet has reached its saturation point, there will be no further increase of motor speed nor decrease of time interval in the operation of the relay. Above 10 times the rated current the motor 100 becomes a synchronous motor, of steady speed with each frequency of alternation, but with speed proportionate to the frequency.

The motor magnet coil 50 is a current energized coil, being directly in series with the transformer coil 45 so that the action of the coil is uniformly proportionate to the current changes induced in the transformer coil from the line wire. The coil 71 of the coupling magnet 70 however is a voltage coil, its conductors 73 and 75 taking off from the two wires leading to the motor magnet coil. In other words the coil 71 is in parallel or in derivation to the coil 50, and is operated by 110 the voltage drop across the terminals of the coil 50 and like the latter its action is proportionate to the line current. The actions, changes or adjustments in the coupling magnet coil however are unable to affect the actions in the motor coil or change the characteristic of the relay. This is because the coupling magnet coil is preferably a high resistance coil and takes but a very small amount 115 of current, a low strength current being sufficient to generate a suitable magnetic pull for operating the spring retarded armature. Therefore, although theoretically the change in impedance in the coupling magnet circuit by cutting in or out the series resistor 76 120

will alter the current in the motor circuit, the effect is practically negligible so far as concerns the characteristic of the relay. It is found that the indicated characteristic 5 faithfully represents the action of the relay under all conditions, and that the action with any set of adjustments can always be reliably reproduced by reproducing the adjustments.

A fine and accurate adjustment is possible 10 with this invention of the time or period of operation. This is due to the relatively high speed of revolution of the disk, which, by speed reduction mechanism, is converted into a slow movement of the time element or travel 15 arm, the latter traveling over a time scale having a large number of subdivisions. This property of close adjustment of the operating interval is particularly valuable for selective switching of several relays in the same system 20 at very small time intervals, although of course in setting the several relays the releasing time of the oil switches must be considered since too close an adjustment may result 25 in the undesired switching out of several oil switches.

The present invention is such that all relays have an absolutely reliable and fixed release 30 characteristic which is one of the most important requirements for the dependability of adjustments and to insure that all of the 35 relays in the network will release properly. With the present invention it is highly advantageous that the coupling mechanism can be adjusted to respond to a current of any desired value within the range of the adjustment, this being due to the principles of the described coupling element and its separation from the time element of the relay.

In order to set the disclosed relay to couple 40 or start at 2 amperes current and to switch or interrupt the line circuit in a period of 5 seconds with an overload current of 2 amperes we proceed by first setting the current adjusting lever 99 to the point 2.0 on scale 102. We 45 then read on the characteristic curve at 2 amperes and find that this corresponds with a 10 seconds period. As we desire the period of 5 seconds we divide 5 by 10 giving 0.5 and we therefore set the time element stop arm 50 89 to the position 0.5 on the scale 91. In practise it is found that the present relay possesses a very high accuracy and with a percentage of error negligibly small. The engaging of the coupling parts 86 and 87 requires but a 55 very small time, in view of the high speed of the motor shaft, and the delay in coupling is well within a satisfactory tolerance of error.

By reason of the fact that the disk starts 60 into rotation well below the rated capacity of the relay and is in continuous rotation in advance of any overload operation there is no loss of time or inaccuracy due to overcoming the initial inertia of the disk. Therefore the disk speed and the time period are free from 65 any irregularity of action from this source

and are thus highly consistent in operation.

The motor disk 60 is shown as a plain circular disk of aluminum but it may be constructed of other form for special purposes and of other non-magnetic metal. The operation of the disk may be initially adjusted at the factory to the required use not merely by the setting of the damping magnet to regulate the rotation, but by the setting of the shading coils on the poles of the motor magnet. The character and the positioning of the shading coils determines the torque or driving action of the motor.

Various modifications may be made under 70 the principles described. While the illustrated relay is rated at 1 ampere the same principles and design can be employed for the construction of a relay of 2 or 5 or greater rating. When used for a 5-ampere relay, 75 for example, the Fig. 2 characteristic may serve, by multiplying the current calibrations by 5.

The adjusting device or index arm 101 for the starting current is shown as moving over a first or a second calibrated scale, the latter being employed when the series resistor 76 is cut into the circuit of the coupling magnet; and manifestly this principle can be carried further by providing a third scale to 80 be used in connection with a still greater resistance to be cut into the circuit.

While an interrupter has been shown in the form of a double pole switch 13 the present invention may be employed in connection with other forms of interrupter. For example in a polyphase transmission system it is frequently practised to employ as an interrupter a single pole oil switch, placing one such switch on each of the parallel conductors, 85 along with a separate relay and current transformer for the operation of the switch. Another arrangement for polyphase systems is as follows. The relay as herein illustrated is specifically adapted for single phase use, but three similar such units may be combined in 90 a single housing, each with its separate pilot switch but all of the pilot switches controlling the same main switch which in turn trips the line circuit interrupter.

The present invention also may be employed in connection with automatically reclosing circuit breakers which are steadily coming into more general use; an instance of which is an oil switch controlled by mechanism which operates after the switch is first 95 opened to reclose it in say 15 seconds after its opening by the relay, and in case the switch is at once reopened by the relay to reclose the switch only after an increased period, say 30 seconds, and upon a third opening of the switch, if it should occur, to leave the switch open.

The characteristic illustrated in Fig. 2 is on 100 the basis of a 60 cycle alternating current, but with a different frequency the principles 105

would be the same; for example with a 50 cycle current the curve would be identical with that shown but moved up on the diagram by the distance of one space or second, so that the constant minimum interval for a high overload would be 6 seconds instead of 5 seconds; and similarly with other frequencies; the characteristic therefore being the same with the various frequencies.

- 10 Certain of the features of the present invention can be employed in connection with a time-limit relay which functions with underload rather than overload as may sometimes be desirable. This, for example, could 15 be effected by a simple reversing of the coupling 86, 87; thus viewing Fig. 9, if the rack 86 be shifted from the rear to the far side of the worm 87 and the worm be rotated in the opposite direction, the coupling will be closed 20 whenever the current falls below the point determined by the adjustment, thus closing the pilot switch and causing the operation of an interrupter or any other instrument suitable for the special purposes.

- 25 It will thus be seen that there has been described a time-limit relay embodying the principles and attaining the objects and advantages of the present invention. Since various matters of operation, combination, 30 arrangement and construction may be modified without departing from the principles of the invention, it is not intended to limit the invention to such matters except so far as set forth in the appended claims.

35 What is claimed is:

1. In an inversely variable time-limit overload relay for controlling electrical circuits, in combination with a tripping means for interrupting or changing the circuit, a 40 variable-speed electromagnetic time motor under control of the current in the circuit, a variable-speed traveling time member adapted to be advanced by the time motor, and to operate the tripping means if and when 45 the time member reaches a predetermined advanced position, a normally open coupling device between the time motor and the time member, and a coupling electromagnet with an armature and adapted at predetermined 50 overload to cause the closing of the coupling device, said magnet being connected in a circuit variably energized from the circuit to be controlled but too weakly when under normal load for the magnet to shift its armature, and adapted to increase progressively in 55 strength with overload of current until at a predetermined overload the magnet shifts its armature and effects such coupling.
2. A relay as in claim 1 and wherein is a 60 transformer operated from the line wire, and said electromagnet is energized by a voltage coil deriving current from said transformer in parallel to the time motor and with such high resistance that the motor speed and re-

lay period are not appreciably affected by the coupling action.

3. In a variable time-limit overload relay for controlling electrical circuits, a tripping means for interrupting or changing the circuit, an electromagnetic time motor operative at variable speed under control of the current in the circuit, a traveling time member adapted to be moved by the time motor and at the end of its travel to operate the 75 tripping means, a normally open coupling device between the time motor and the time member, and an electromagnetic coupling means for causing the closing of the coupling device with a predetermined current over- 80 load, and the reopening thereof with a restoration of normal current, comprising a magnet in a circuit variably energized from the circuit to be controlled, an armature connected with the coupling device, and a retracting spring for the armature of such strength as to prevent shift of the armature during normal load and until a predetermined overload. 85

4. In a variable time-limit overload relay, a tripping means for interrupting or changing a circuit, an electromagnetic time motor comprising means rendering it operative at variable speed under control of the current in the circuit when the current is above the rated capacity of the relay, a traveling time 90 member adapted to be moved from a predetermined starting position at variable speed by the time motor and after travel to a predetermined position to operate the tripping means, means for varying the predetermined 95 starting position to adjust the extent of travel, a normally open coupling device between the time motor and the time member, and an electromagnetic coupling means for causing the closing of the coupling device when the 100 current in the circuit rises above a predetermined magnitude, and the opening thereof upon a predetermined lowering of current. 105

5. In a variable time-limit overload relay for controlling electrical circuits, a tripping means for interrupting or changing the circuit, an electromagnetic time motor operative at variable speed under control of the current in the circuit, and normally in continuous rotation when the current is above 110 the rated capacity of the relay, a traveling time member adapted to be moved at variable speed by the time motor and after a predetermined travel to operate the tripping means, a 115 normally open coupling device between the time motor and the time member, and an electromagnetic coupling means for causing the closing of the coupling device when the current in the circuit rises above a predetermined magnitude, said coupling device comprises a speed reducing worm and rack, the worm turned by the time motor and the rack moving the time member, the worm and rack being engageable and disengageable by a relative movement of the rack in a lateral direc- 120 125 130

tion tangent to the rotation of the worm, and the coupling means having a yielding connection arranged to bring said worm and rack into or out of engagement.

5 6. In a variable time-limit overload or other relay for controlling electrical circuits, a tripping means, a variable-speed electromagnetic disk motor operative at higher speeds with higher currents in the circuit, a 10 variable-speed traveling time member adapted to be moved by the time motor and to operate the tripping means, and an electromagnetic means for coupling and uncoupling the time motor and the time member, under control of the current in the circuit; said motor comprising an electromagnet with its pole or poles of restricted section to limit the magnetic flux and thereby limit the motor to a predetermined maximum speed, at a predetermined critical current, while permitting variable speeds below such critical current, whereby the time period of the relay is variable down to a predetermined minimum period but is maintained against falling below 25 such predetermined minimum.

7. In an inversely variable time-limit overload relay for controlling electrical circuits, in combination with a tripping means for interrupting or changing the circuit, a variable-speed electromagnetic time motor under control of the current in the circuit, a variable-speed traveling time member adapted to be advanced by the time motor, and to operate the tripping means if and when the time member reaches a predetermined advanced position, a normally open coupling device between the time motor and the time member, and a coupling means adapted at predetermined overload to cause the closing of the 40 coupling device; said time motor being a disk motor having its magnet poles of such reduced section as to set the magnetic saturation point at a value to produce a time period of operation which will be constant above a predetermined value of over current, whereby the tripping period may not be below a predetermined minimum.

8. In an inversely variable time-limit overload relay for controlling electrical circuits, a tripping means for interrupting or changing the circuit, a time motor operative at variable speed under control of the current in the circuit, a variable-speed traveling time member adapted to be moved by the time motor and at the end of its travel to operate the tripping means, a normally open coupling device between the time motor and the time member, and an electromagnetic coupling 55 means for causing the shifting of the coupling device under control of the current in the circuit, comprising an electromagnet, an armature therefor connected to the coupling, a retracting spring for the armature, and 60 means for adjusting the tension of the spring

to predetermine the strength of field or current to effect the coupling.

9. A relay as in claim 8 and wherein the spring adjusting means comprises a continuously adjustable support to which the spring is attached, and an index for indicating the adjustment thereof. 70

10. A relay as in claim 8 and wherein is a series resistance for the circuit of the electromagnet, and means for cutting in or out 75 said resistance to shift the range of adjustment of the coupling means.

11. In a variable time-limit overload relay for controlling electrical circuits, a tripping means for interrupting or changing the circuit, an electromagnetic time motor operative at variable speed under control of the current in the circuit, and normally in continuous rotation when the current is above the rated capacity of the relay, a traveling time member adapted to be moved at variable speed by the time motor and after a predetermined travel to operate the tripping means, a normally open coupling device between the time motor and the time member, an electromagnetic coupling means for causing the closing of the coupling device when the current in the circuit rises above a predetermined magnitude, and means for cutting resistance into or from the electromagnetic coupling means 80 to shift its range of action. 85

12. In an inversely variable time-limit overload relay for controlling electrical circuits, a tripping means for the circuit, a time motor operative at variable speed under control of the current in the circuit, a variable-speed traveling time member adapted to be moved by the time motor and at the end of its travel to operate the tripping means, a normally open coupling device between the time motor and the time member, an electromagnetic means for closing the coupling device under control of the current in the circuit, operable when the current rises above normal to a predetermined overload, and yielding means associated with the coupling device for preventing excess actuation of the time member. 100 105

13. A relay as in claim 12, and wherein the coupling device comprises a worm driven by the motor and a rack for moving the time member, and the means for preventing excess actuation comprises a resilient mounting for the rack whereby it may be disengaged from the worm by the rotation of the latter. 110 115

14. In a variable time-limit overload relay, a tripping means for the circuit, an electromagnetic time motor operative at variable speed under control of the current in the circuit, a traveling time member adapted to be moved at variable speed by the time motor and after a predetermined travel to operate the tripping means, a normally open coupling device between the time motor and the time member, and coupling means for causing the 120 125 130 135

closing of the coupling device when the current in the circuit rises above a predetermined magnitude, comprising an electromagnet with shiftable armature, means for restraining the armature comprising a device for adjusting its restraining force to determine the action of the magnet, and means for cutting resistance into or from the circuit of the electromagnet to shift its range of action.

10 In testimony whereof, we have affixed our signatures hereto.

ERNST BAUMBERGER.
